HI-RISE POULTRY BUILDING

George E. France, Rte. 2, Box 60,
Oswego, Ill. 60543

Filed May 8, 1972, Ser. No. 251,602

Term of patent 14 years

Int. Cl. D25—03

U.S. Cl. D13—1 R

FIG. 1

FIG. 4

FIG. 2

FIG. 3

FIG. 5

FIG. 6

FIG. 1 is a top plan view of the hi-rise poultry building embodying my new design.

FIG. 2 is an end and side perspective of the hi-rise poultry building shown in FIG. 1.

FIG. 3 is a perspective view of the hi-rise poultry building shown in FIG. 1 and FIG. 2, showing the end and side opposite to that shown in FIG. 2.

FIG. 4 is an end elevation of the hi-rise poultry building shown in FIGS. 1, 2, and 3.

FIG. 5 is an end elevation of the hi-rise poultry building showing the end opposite to that shown in FIG. 4.

FIG. 6 is a sectional elevation of the hi-rise poultry building embodying my new interior design, the view being intermediate the ends of the building taken at 6—6 in FIG. 1.

In FIG. 2 and in FIG. 3, portions are broken away and omitted to indicate indeterminate length.

I claim:

The ornamental design for a hi-rise poultry building, as shown and described.
